(57) **CLAIM**

What is claimed is an ornamental design for a magnet clip mount, as shown and described.

DESCRIPTION

FIG. 1 is a front, left, top view of a magnet clip mount showing our new design;

FIG. 2 is a front elevational view thereof;

FIG. 3 is a rear elevational view thereof;

FIG. 4 is right side elevational view thereof;

FIG. 5 is a left side elevational view thereof;

FIG. 6 is a top plan view thereof;

FIG. 7 is a bottom plan view thereof; and,

FIG. 8 is rear, right, top view thereof.

wherein the broken lines are included for illustrative purposes only and form no part of the claimed design.

1 Claim, 5 Drawing Sheets
